UNITED STATES PATENT OFFICE.

CHARLES F. COPELAND, OF BOSTON, MASSACHUSETTS, ASSIGNOR TO
JOSEPH HARRIS, TRUSTEE, OF SAME PLACE.

AUTOMATIC HYDROCARBON-FEEDING APPARATUS FOR CARBURETORS.

SPECIFICATION forming part of Letters Patent No. 308,877, dated December 9, 1884.

Application filed April 23, 1884. (No model.)

To all whom it may concern:

Be it known that I, CHARLES F. COPELAND, a citizen of the United States, residing at Boston, in the county of Suffolk and State of Massachusetts, have invented certain new and useful Improvements in Automatic Hydrocarbon-Feeding Apparatus for Carburetors; and I do hereby declare that the same are fully described in the following specification and illustrated in the accompanying drawings.

This invention relates to improvements in automatic hydrocarbon-feeding apparatus for supplying hydrocarbon to gas machines or carburetors; and it is carried out as follows, reference being had to the accompanying drawings, where—

Figure 1 represents an end view of the invention, and Fig. 2 represents a central longitudinal section on the line A B in Fig. 1. Fig. 20 3 represents a cross-section on the line C D in Fig. 2, as seen from the right end of said Fig. 2; and Fig. 4 also represents a cross-section on the line C D, as seen from the left end of Fig. 2.

Similar letters refer to similar parts wherever they occur on the different parts of the drawings.

a is the cylinder, within which is located the rotary motor b, having the screw-shaped wing b', and arranged upon the central shaft 30 or spindle, b'', located in suitable bearings in the cylinder a, as usual.

c is the gas-supply pipe leading to the motor b, and terminating within the latter as the upwardly-projecting pipe c', as usual.

35 d is a branch pipe connected to the gas-supply pipe C in the ordinary manner, through which atmospheric air is forced with the gas into and through the motor b.

e represents the hydrocarbon within the cylinder or case a, such hydrocarbon being kept at a proper level above the motor-shaft b'', as shown in Fig. 2, by a suitable float regulating device.

To one end of cylinder a is attached the box 45 or chamber f, the upper portion of which is in open communication with the cylinder a by means of the opening a', made through the end of cylinder a where the box f is attached, as shown in Figs. 2 and 3, to allow the gas and 50 air to pass from the cylinder a and its motor b into the upper part of the chamber f. The

lower part of said chamber f is in open communication with that part of cylinder a containing the hydrocarbon by means of the perforation f', (shown in Fig. 3,) so as to keep the 55 hydrocarbon g in chamber f on a level with the hydrocarbon e in cylinder a in the ordinary manner.

h is the hydrocarbon-supply pipe leading to chamber f, and connected on the inside of the latter with a valve-box, h', having valve h'', delivery-opening h³, valve-spindle h⁴, hinged lever h⁵, stationary fulcrum-support h⁶, and float h⁷, in the usual manner, for regulating the supply of hydrocarbon, and to retain its upper level at a normal one during the operation of the apparatus.

Within the box f is located upon the end of motor-spindle b'' the small pinion b³, that gears into the teeth of gear-wheel i, secured to the 70 spindle i', that is free to move in suitable bearings within the box f, as shown in Fig. 2.

To the spindle i' is secured the disk, rim, or wheel k, having pivoted to its peripheral spindles k' k'' the movable buckets k'' k'', as shown 75 in Figs. 2 and 4.

Above the spindle i' is secured to the wall of chamber f the spring-bar l, (shown in Figs. 2 and 4,) that serves for the purpose of automatically tipping over each bucket k'' when it reaches its highest, or nearly so, position, and to deliver the hydrocarbon from such bucket into the trough m after it is taken up from the contents of chamber f, when such bucket passes through the liquid contents of said 85 chamber, as represented in said Figs. 2 and 4.

The trough m communicates with the downwardly-projecting pipe n, that leads to the carburetor, and by this means a constant supply of hydrocarbon is taken up by the pivoted 90 revolving buckets k'', and delivered through the pipe n to the carburetor, where the gas or air is to be enriched. The upper end of pipe n opens into the upper portion of chamber f, so as to allow the gas and air forced from the 95 motor b into said chamber to pass down through said pipe n with the hydrocarbon supplied from the buckets k'' k''.

The operation of the apparatus is as follows: Air and gas being forced into the cylinder a 100 by means of the pipes c d, and made to pass through the upper portion of motor b, the lat-

ter is caused to rotate around its axis, and by means of the gears b^3 i a rotary motion is imparted to the wheel k , causing its pivoted buckets k'' k''' to dip into the hydrocarbon g in box f , and to take up a portion of such hydrocarbon, and to empty it into the trough m as the buckets successively come in contact with the tipping-spring l , as described.

What I wish to secure by Letters Patent, and to claim, is—

In combination, the cylinder a , rotary motor b b' , air and gas pipes c d , gears b^3 i , box f ,

spindle i' , wheel k , with its pivoted buckets k'' k''' , spring l , trough m , delivery-pipe n , hydrocarbon-supply pipe h , with its valve h' h'' , lever h^5 , and float h^7 , all arranged and combined in a manner substantially as set forth and described.

In testimony whereof I have affixed my signature in presence of two witnesses.

CHARLES F. COPELAND.
